UNITED STATES PATENT OFFICE.

LUDWIG DÜRR, OF BREMEN, GERMANY.

OIL-VAPOR LAMP.

SPECIFICATION forming part of Letters Patent No. 453,440, dated June 2, 1891.

Application filed July 28, 1890. Serial No. 360,240. (No model.)

To all whom it may concern:

Be it known that I, LUDWIG DÜRR, a subject of the Free State of Bremen, residing in Bremen, German Empire, have invented an 5 Improvement in Oil-Lamps; and I do hereby declare the following to be a full, clear, and exact description of my invention.

In this oil-vapor lamp the illuminating-flame is intended to impinge against the vaporizing-coil and thus be utilized to convert 10 the oil into vapor.

In the accompanying drawings, Figure 1 is a side elevation, partly in section; Fig. 2, a detailed end view of the vaporizing-coil and 15 burner.

In the drawings, *a* represents a suitable tank for containing the liquid fuel and provided with a funnel *h* and stop cock *g*, through which the tank may be filled.

20 A pipe *b*, provided with a regulating-valve *f*, conducts the oil to the vaporizer. This consists of a coil of pipe *c*, forming a continuation of the conduit-pipe *b* and located within a casing *A*. The end of the coil is extended and carried back longitudinally along the outer side thereof, and its rear end is bent 25 inwardly and turned forward centrally of the coil, thus providing a burner *d*, which directs the flame centrally through the coil from its rear to its front end and through an opening 30 in the front of the case *A*. A valve is provided in the burner, as at *e*. The casing is formed with air-conduits *2*, leading from the front end rearward and discharging in proximity to the burner, so that when the vapor

is ignited the flame will induce a current of air within the casing, which, mingling with the vapor, will produce an illuminating-fluid.

In operating the device a suitable piece of wick or wadding steeped in petroleum, is 40 placed in the casing and igniting, thus heating the coil and burner and vaporizing the oil, and when the valve *e* is opened the vapor issuing from the burner will be ignited, producing the illuminating-flame, as represented. 45 This flame, as before stated, passes from end to end of the coil, and is thus utilized to vaporize the oil therein so long as the valves are open.

I claim as my invention—

50 In combination, the tank, the conduit-pipe, a coil of tubing forming a cylindrical channel for the flame, a casing inclosing the coil and having a front plate with an opening in line with the center of the channel, the conduit *2*, extending from the front of the casing to rear of the coil and communicating through an opening in the rear with the channel, the coil having an extension from its front to its rear end, passing between the coil 55 and the inside of the casing, and terminating in a burner-opening within the coil, substantially as described.

55 In witness whereof I have hereunto set my hand in presence of two witnesses.

LUDWIG DÜRR.
